Almon Ralph Jr.

ATTORNEY.

UNITED STATES PATENT OFFICE.

ROBERT F. BOLAM, OF TRAFFORD, PENNSYLVANIA.

CUE.

1,407,512.

Specification of Letters Patent. Patented Feb. 21, 1922.

Application filed May 13, 1920. Serial No. 381,127.

To all whom it may concern:

Be it known that I, ROBERT F. BOLAM, a citizen of the United States, residing at Trafford, in the county of Westmoreland and State of Pennsylvania, have invented certain new and useful Improvements in Cues; and I do hereby declare the following to be a full, clear, and exact description of the invention, such as will enable others skilled in the art to which it appertains to make and use the same.

This invention relates to new and useful improvements in cues and has for its primary object the provision of means for detachably securing the tip to the stick of the cue and which will firmly secure said tip to the stick and increase in its holding action as the pounding or use of the device is increased.

Another object of this invention is the provision of a cue of the above stated character which shall be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description, and accompanying drawings, in which:-

Figure 1 is a side elevation of a cue constructed in accordance with my invention,

Figure 2 is a sectional view of the same,

Figure 3 is a sectional view taken on the

line 3-3 of Figure 2,

Figure 4 is a similar view taken on line 4-4 of Figure 1,

Figure 5 is a sectional view, illustrating the tip holding device,

Figure 6 is an end view, illustrating the same,

Figure 7 is a side elevation, illustrating a key.

Referring in detail to the drawing, the numeral 1 indicates as an entirety a cue consisting of the usual stick 2 constructed from any material suitable for the purpose and has secured to its handle or butt end a cushion pad 3 by a metallic band or col-

lar 4.

The other end or tip end of the stick 2 is reduced to form a ferrule receiving portion 5 which is screw threaded and is adapted to have threaded thereon a ferrule 6 constructed from any material suitable for the purpose. The ferrule receiving portion 5 at its free end is further reduced to form an extension 7 which is slightly spaced from the wall of the ferrule 6 as clearly shown in the drawing to permit a tip holding element 8 to be threaded into the end of said ferrule. The tip holding element 8 is constructed from any material suitable for the purpose and consists essentially of an annular body or ring 9 that has its inner wall concaved as illustrated at 10 defining an internal annular flange 11 and a shoulder at the ends of said ring. The ring 9 has formed integrally therewith a screw threaded neck 12 adapted to be threaded into the end of the ferrule 6. A tip 13 constructed from any material suitable for the purpose consists of a head portion 14 formed integrally with a body portion 15. The body portion 15 is of a diameter slightly smaller than the head portion 14 and is compressed and inserted within the ring 9 and allowed to expand and conform to the concave face 10 of said ring and be tightly gripped and held within said ring by the annular internal flange 11. The inner end of the body 15 rests against the extension 7 of the ferrule receiving portion 5 of the stick 2 thereby cooperating with the ferrule and tip securing element in forming a firm connection between the tip and the stick and it will be seen that the tip is securely held in place and the increased use of the devise has a tendency to further drive the tip into engagement with the stick and within the ring 9. It is also to be noted that the tip can be readily removed whenever desired by detaching the tip securing element from the ferrule 6 or the ferrule can be detached from the stick and applied to another stick in case of breaking or wear-

ing out of the former stick.

The body of the tip is provided with grooves 16 to receive a substantially U-shaped key 17 which is also received by notches 18 formed in the flange 11 whereby the tip is held against rotation.

While I have shown and described the preferred embodiment of my invention, it will be understood that minor changes in construction, combination and arrangement

of parts may be made without departing from the spirit and scope of the invention as claimed.

Having thus described my invention what I claim is:—

1. In combination, a tip of the class described having a projection, a holder having a recess receiving said projection, said holder having a flange at the entrance to the recess to directly engage said projection, a key associated with the projection having a bridge portion, said flange being provided with a slot to receive said key to prevent relative turning of the tip and holder, and said bridge portion of the key resting on the stick.
2. In combination, a tip of the class described having a projection, a holder having a recess receiving said projection, said holder having a flange at the entrance to the

recess to directly engage the projection, a key associated with the projection and said flange being provided with a slot to receive said key to prevent relative turning of the tip and holder.

3. In combination with a tip of the class described, a projection thereon, a holder having a recess to receive said projection, a stick mounting the holder, said projection and holder having slots, a substantially U-shaped key having its arms disposed in said slots to prevent relative turning of the tip and holder.

25

In testimony whereof I affix my signature in presence of two witnesses.

ROBERT F. BOLAM.
